US0D1010757S

(12) **United States Design Patent** (10) Patent No.: **US D1,010,757 S**
(45) Date of Patent: ** Jan. 9, 2024

(54) **INFLATABLE OBSTACLE**

(71) Applicants: **Robin Whincup**, Port Charlotte, FL (US); **Michael Robin Whincup**, Bradenton, FL (US)

(72) Inventors: **Robin Whincup**, Port Charlotte, FL (US); **Michael Robin Whincup**, Bradenton, FL (US)

(**) Term: **15 Years**

(21) Appl. No.: **29/838,819**

(22) Filed: **May 16, 2022**

Related U.S. Application Data

(63) Continuation of application No. 29/749,474, filed on Sep. 4, 2020, now Pat. No. Des. 956,159, which is a continuation of application No. 29/669,525, filed on Nov. 8, 2018, now Pat. No. Des. 895,756.

(57) **CLAIM**

The ornamental design for an inflatable obstacle, as shown and described.

DESCRIPTION

FIG. 1 is a front and right side perspective view of an inflatable obstacle in accordance with the new design; FIG. 2 is a front perspective view thereof;

FIG. 3 is a top, front, and left side perspective view thereof; FIG. 4 is a rear and left side perspective view thereof; and, FIG. 5 is a rear and right side perspective view thereof.

The bottom view is flat and unornamented and forms no part of the claimed design. The portions of the figures shown in contrast, along with the parts of the figures shown in broken-line perimeter, illustrate portions of the inflatable obstacle that form no part of the claimed design.

1 Claim, 5 Drawing Sheets
